UNITED STATES PATENT OFFICE.

AUGUSTE JEAN HENRI LAUNAY, OF PARIS, FRANCE.

PENHOLDER.

1,367,880.

Specification of Letters Patent.

Patented Feb. 8, 1921.

Application filed March 24, 1920. Serial No. 368,345.

To all whom it may concern:

Be it known that I, AUGUSTE JEAN HENRI LAUNAY, a citizen of the French Republic, and resident of Paris, have invented certain new and useful Improvements in Penholders, of which the following is a specification.

The present invention relates to that class of pen holders in which the pen is secured in position on the holder by means of resilient parts and the object of the novel device consists in providing resilient means of simple construction for efficiently maintaining the pen within the holder.

The invention consists substantially in that the sleeve of the pen holder is provided with two longitudinal grooves upon the convex side of which bears the oppositely curved face of the stem of the pen, and in that a U shaped spring engaged within the sleeve opposite the grooves and having its two end portions conveniently curved in an upward direction, presses against the longitudinal edges of the said stem, whereby the pen is pressed against the grooves and the pen firmly maintained in the holder.

In the accompanying drawings, given by way of example,

Figure 1 is an axial section through the pen holder with a pen engaged therein.

Fig. 2 is a cross section of same on line 2—2 of Fig. 1.

Fig. 3 is a perspective view of the U shaped spring.

Sleeve 1 is provided with two longitudinal grooves 3 and surrounded by a ring 6.

Within the sleeve, and opposite the grooves 3 is inserted a U shaped spring 4, the curved end portions 5 of which press 40 against the edges of the stem 2 of the pen, whereby the latter is squeezed between the spring and the grooves.

It may be readily understood that the pen, having its stem squeezed between both 45 grooves 3 and the end portions 5 of the spring plate 4, is firmly maintained in position. The ring 6 protects the grooved sleeve against eventual deformations.

Having now fully described my said invention, what I claim and desire to secure by Letters Patent, is:

A pen holder comprising a sleeve, two longitudinal grooves provided on said sleeve, the convex side of said grooves being turned 55 toward the center of the sleeve, a U shaped spring plate provided within the sleeve opposite said grooves, upwardly curved end portions on said spring plate, whereby the stem of a pen, engaged within the sleeve 60 between said grooves and the spring blade, is pressed against the said grooves and firmly maintained within the sleeve and a ring surrounding the said sleeve.

In testimony whereof I have hereunto set 65 my hand in presence of two witnesses.

AUGUSTE JEAN HENRI LAUNAY.

Witnesses:

HENRY T. WILCOX,
GEORGES DE URSLUCK.
